UNITED STATES PATENT OFFICE.

MICHAEL HOLROYD SMITH, OF HALIFAX, COUNTY OF YORK, ENGLAND.

APPARATUS TO BE USED IN ELECTRIC RAIL OR TRAM WAY SYSTEMS.

SPECIFICATION forming part of Letters Patent No. 297,306, dated April 22, 1884.

Application filed December 11, 1883. (No model.) Patented in England October 24, 1883, No. 5,065.

To all whom it may concern:

Be it known that I, MICHAEL HOLROYD SMITH, a subject of Her Majesty the Queen of Great Britain, residing at Halifax, in the county of York, England, have invented certain new and useful Improvements in Apparatus to be Used in Electric Rail or Tram Way Systems, of which the following is a specification.

This invention relates to apparatus to be employed for carrying and collecting the electric current, and passing the same to the driving-motor of the engine or car, as also to the method of "laying" the conductor. In a previous application for Letters Patent I have described a system of electric rail or tram ways in which the conducting-bands were carried in an underground channel, the current being collected therefrom by means of trolleys or bogies traveling therein and moving with the car or engine.

My present invention consists of modifications or improvements on the system there described, by the application of which the use of trolleys or bogies may be dispensed with, as the conductors are formed of more or less longitudinally-slotted tube-shaped sections, in which suitable shuttles and spring-collectors are caused to travel, the current being passed from such collectors to the driving-motor by means of suitable connections.

A further portion of my present invention consists in the method of laying and supporting said tubular conductor and its superposed road-bed or covering, by means of which the shuttle and spring-collectors, as also sections of the tubular conductors, may be readily removed for repair or for other purposes.

To clearly set forth and explain my invention, reference is made to the accompanying drawings, which form part of this specification, and in which like letters of reference refer to corresponding parts of the apparatus in different figures.

Figure 1 represents a side elevation of the channel containing the tubular conductor, which, with a portion of the collector, is shown partially in section. Fig. 2 represents an end view, showing how the tubular conductor may be held in position, and also showing the removable top plate or road-bed. Fig. 3 repre-

sents a plan or top view of the removable top plate, a portion of which is broken away to show the supporting-upright. Figs. 4, 5, and 6 represent in side elevation modifications of the form of collector shown in Figs. 1 and 2, 55 while Fig. 7 represents in plan, and Figs. 8 and 9 in sectional end elevation and side elevation, respectively, modifications of the arrangements for supporting the tube and road-bed plate shown in Figs. 2 and 3. In all the 60 arrangements it is intended that when the shuttle is moved in either direction the spring-connections between the shuttle-heads shall be slightly compressed, causing said springs to be bulged out, so as to come in intimate contact 65 with the tubular conductor and take up the current therefrom, which is then passed to the shuttle-heads, and from them through suitable connections to the motor.

In Figs. 1 and 2 shuttle-heads *a* are represented as being connected not only by spiral-spring conductors *b*, but also by a double-headed bolt or connecting-rod, *c*, the heads of which bear against the interior faces of suitable shoulders formed in the shuttle-heads, as 75 shown, the space behind such shoulders, and within which the bolt-heads play, being sufficient to allow the spiral *b* to be bulged out before the forward shuttle-head, *a*, will be pushed by said bolt, one or both ends of which are 80 provided with nuts for the purpose of regulating the compression of the springs. As shown in said Figs. 1 and 2, the current passes from bolt *c*, through arms *d*, connecting pieces *e f g* to the motor. The pieces *f* are preferably 85 of spiral-spring form, in order that the shuttle may be gradually started and stopped.

The parts *G* are attached to and move with the engine or car, and pass sufficiently far through the slot in the bed-plate *H* to keep 90 said slot clear and open. The conductors *g*, as shown in Fig. 1, pass through or by parts *G*, but are insulated therefrom. In Fig. 4 a connecting-bolt, *c'*, is represented as being attached through arms *d'*, which are attached 95 directly to or are integral with the shuttle-heads *a*, the "play" of bolt *c'* being given in this arrangement by means of the sliding of said bolt in the arms *d'*.

In Fig. 5 the spiral springs *b* are replaced 100

by two or more curved springs, which are bulged by the tapering faces made on the rod or bolt *c*, as shown. In Fig. 6 the springs *b* are represented as being formed of a series of 5 rings riveted or otherwise electrically connected to each other and to the shuttle-head *a*. The general construction of this form is substantially the same as shown in Fig. 4.

In Figs. 1, 2, and 3 the tubular conductor *A* is represented as being carried in a series of insulating-supports, *B*, which in turn are secured in position by supporting-pieces *C* (cast with and forming part of the plate *H*) and *D*, the latter being held and supported by means 15 of a wedge, *E*, driven between it and the part *F*, which, like part *C*, is attached to or forms part of the road-bed plate *H*. Said road-bed plate is held in position by means of a **T** or other suitable slide-piece, *h*, attached thereto, 20 and adapted to slide in recesses or behind riveted lugs *i* upon the walls, as shown in Figs. 2 and 3. This arrangement enables sections of the road-bed plates to be raised, when the part *D* may be readily removed and a section 25 of the tubular conductor taken out. The road-bed section removed should be long enough to enable the shuttle and its connected parts to be placed in the main tube, the removed section being subsequently replaced and secured. 30 It will be understood that before any road-bed section is removed or after it is replaced the corresponding parts of tubular conductor are connected or disconnected, as the case may be, and this may be accomplished by means of 35 suitable hand-holes placed at the requisite distance apart in the road-bed.

In Figs. 7, 8, and 9 the top opening to the channel is represented as approximately in the center of the road-bed plates; but, as in 40 Figs. 1 and 2, the removable section *H* is held in position and supported by the part *h*, which passes behind the lugs *i*, riveted to or forming part of wall *I*, the support *C* and part *F* being represented as being riveted to the opposite 45 wall-plate, *I'*, the clip *D* being in this case held by the wedge *E* against the side instead of against the top portion of the wall, *I'*. The

operation of the parts being the same as described with reference to Figs. 2 and 3, further reference is unnecessary.

Having described my invention and set out how the same may be practically employed, what I claim, and desire to secure by Letters Patent, is—

1. In an electric rail or tram way, the combination, with a tubular conductor, of a shuttle composed of the expansible spring-collector *b* and heads *a*, located and adapted to travel in said tubular conductors, to collect and transmit the current through suitable connections 60 with said shuttle to the motor, substantially as and for the purpose described.

2. In an electric tramway, substantially as shown and described, the combination of the shuttle composed of the heads *a* and an expansible spring between said heads, with a connecting-bolt to limit the movement of the heads toward and from each other, and thereby the expansion and contraction of the spring-collector, substantially as described.

3. In an electric tramway, the conductor *A* and the shuttle located therein, combined with the coiled spring *f*, connected with said shuttle and with the car, substantially in the manner and for the purpose described.

4. In electric rail or tram ways, the combination of the tubular conductor *A* and insulating-support *B* with supports *C*, *D*, and *F*, wedge *E*, and cover *H*, all substantially as and for the purposes set forth.

5. In an electric rail or tram way, the walls of the channel, a removable cover, *H*, having attached thereto the wedge-holding projection *F*, the supporting-pieces *C*, and slide-piece *h*, combined with the lugs *i* on the wall of the 85 channel, to receive the piece *h*, and the movable piece *D*, held by the wedge, all substantially as described.

MICHAEL HOLROYD SMITH.
